UNITED STATES PATENT OFFICE

168,837

OBSERVATION CAR

Ralph W. Haman, Flossmoor, Clarence V. Norby,
 Chicago, and Donald W. Doman, Harvey, Ill.,
 assignors to Pullman-Standard Car Manufacturing
 Company, Chicago, Ill., a corporation of
 Delaware

Application March 19, 1952, Serial No. 18,964

Term of patent 14 years

(Cl. D66—1)

To all whom it may concern:

Be it known that we, Ralph W. Haman, Clarence V. Norby, and Donald W. Doman, citizens of the United States of America, and residents, respectively of Flossmoor, county of Cook, and State of Illinois, Chicago, county of Cook, and State of Illinois, and Harvey, county of Cook, and State of Illinois, have invented a new, original, and ornamental Design for an Observation Car, of which the following is a specification, reference being had to the accompanying drawings, forming part thereof.

In the drawings—

Fig. 1 is a side elevational view of an observation car;

Fig. 2 is a fragmentary perspective view of an observation car showing our new design;

Fig. 3 is a top plan view of Fig. 2;

Fig. 4 is a side elevational view thereof;

Fig. 5 is an elevational view taken on line 5—5 of Fig. 3;

Fig. 6 is an elevational view taken on line 6—6 of Fig. 3;

Fig. 7 is a perspective view of the interior of the observation car looking toward the rear; and

Fig. 8 also is a perspective view of the interior, looking generally toward the front of the car.

The dominant features of our design reside in those portions shown by means of full lines on the drawings.

What is claimed is:

The ornamental design for an observation car, substantially as shown and described.

RALPH W. HAMAN.

CLARENCE V. NORBY.

DONALD W. DOMAN.
